LOCKING DEVICE FOR FOLDING IRONING
TABLE LEGS

Herbert L. Voigt and Raymond W. Gerlach, Milwaukee, Wis., assignors to Gender Paeschke & Frey Co., Milwaukee, Wis., a corporation of Wisconsin

Application July 3, 1948, Serial No. 37,006

2 Claims. (Cl. 38—117)

1

This invention relates to improvements in folding ironing tables, particularly to a locking device for locking the folding legs of the table in extended position.

In tables of this type the front and rear legs are connected by links so that they swing in unison from folded to extended position. By locking either the front or the rear legs with respect to the board both sets of legs will be held in extended position. It is essential, however, that the lock be under tension to secure rigidity of the legs while in extended position. Heretofore, the locking rod loosely encircled one of the legs and was loosely held against its outer surface by a guide, or was pivotally carried by a slide which moved along one of the legs. The mere locking of the rod in the extended position of the legs did not put any tension between the rod and the leg and the considerable play resulting made the legs wobbly. Because it is impractical to make a tight fit between the slide and the leg, the legs will wobble in extended position.

It is an object of this invention, therefore, to provide a folding ironing table in which the legs when locked in extended position are rigidly held and are not wobbly.

Another object of the invention is to provide a folding ironing table which has a leg-locking mechanism of simple and inexpensive construction which will automatically be placed under tension when the legs are locked in extended position.

These objects are obtained by: providing one of the interconnected front and rear legs with a longitudinally extending slot; pivotally connecting one end of a locking rod to the ironing table; rigidly mounting on the other end of the locking rod a shoe which is slidably engaged with said slot; and providing said shoe with a tongue which is brought into pressure bearing relation with the slotted leg when the legs are in the extended position. In the unfolding of the legs the angular relationship between the slotted leg and the locking rod increases. This inherent characteristic is utilized to swing the shoe so that its tongue is brought into pressure engagement with the leg approximately when said leg reaches its extended position. This tightens and places the sliding connection between the leg and said shoe under pressure. Thus a rigid connection is obtained between the locking rod and the leg in the extended position thereof. Such rigid connection prevents the legs from wobbling. Latching means is carried by the leg to engage the shoe

2

when it is in the extended position. Such latching means is positioned so as to be automatically engaged and readily disengaged.

The novel features, which are considered characteristic of the invention, are set forth with particularity in the appended claims. The invention itself, however, both as to its organization and its method of operation, together with additional objects and advantages thereof, will best be understood from the following description of a specific embodiment when read in connection with the accompanying drawing, in which:

Fig. 1 is a view in side elevation of an ironing table embodying the present invention;

Fig. 2 is an enlarged fragmentary view taken from the line 2—2 of Fig. 1;

Fig. 3 is an enlarged fragmentary view taken from the line 3—3 of Fig. 1;

Fig. 4 is a sectional view taken on line 4—4 of Fig. 2;

Fig. 5 is a sectional view taken on line 5—5 of Fig. 2; and

Fig. 6 is a perspective view of the shoe.

Referring to the drawing by reference numerals, the ironing table 10 is of customary design and is supported by a front leg 12 and a pair of rear legs 14 (only one shown). The legs are pivoted to the table at 16 and 18, respectively. As is conventional with this construction the rear legs spread apart as they move from folded to extended position to give greater stability to the table in such position. The linkage by which the spreading is accomplished forms no part of this invention and will not be herein described.

A pair of links 20 interconnect each of the rear legs with the front leg at the pivotal connections indicated at 22 and 24, respectively. By reason of this interconnection of the front leg and rear legs they swing in unison from the folded position to the extended position. Thus if either the front leg or the rear legs are locked with respect to the board when in extended position, both the front and rear legs will be held in such position.

In the exemplification herein described the locking mechanism includes a locking rod consisting of a pair of rods 26 and 27 pivotally mounted to the board by being pivotally interconnected with the pivots 18. The forward ends of these rods are rigidly secured to a shoe 28 as indicated at 29, such rigid interconnection being accomplished by riveting or projection welding or otherwise securing each of the rods to the bottom of the shoe. The shoe is formed so that it has an upper bridge 30 which is slotted at the

sides to make a T 32. The forward portion of the shoe has an upwardly projecting tongue 34 braced against bending with respect to the body of the shoe by a formed rib 36. The front leg 12 has a forward wall 38 having cut therethrough a longitudinally extending slot 40. The width of the slot 40 is such as to slidably accommodate the neck part of the T 32. At its upper end the slot 40 has an enlarged opening 42 which will permit the bar of the T 32 to pass through the forward wall during assembly of the leg and locking bar. This opening, however, is positioned beyond the normal travel of the shoe 28 during folding and unfolding of the legs. Hence the T 32 will maintain the shoe 28 in sliding engagement with the forward wall 38 as the legs are moved from folded to extended position. It is desirable to give the undersides of the cross bar of the T a slight taper, as indicated at 44 (see Fig. 5) so that only a very small part of the edge of the slot 40 will be normally engaged by the T 32. This will prevent the T from scraping an unsightly amount of the protective coating from the outer surface of the forward wall 38.

In the folded position of the legs the locking rods 26 and 27 are substantially parallel to the front leg 12 and the ends of those rods are bent downwardly so that the shoe 28 is tipped with respect to the inner surface of the forward wall 38 so that the end of the tongue 34 is spaced from that wall, as generally indicated at 35. As the legs unfold the angle between the leg 12 and the rods 26 and 27 increases and the end of the tongue 34 moves toward the inner surface of wall 38. As the legs approach the fully extended position the tongue 34 will engage the wall 38 under pressure and draw the T 32 tightly against the edge of slot 40. This takes out all of the looseness of the sliding fit between the shoe 28 and the leg 12 thus making a rigid lock between that leg and the table. This keeps the legs from wobbling while in extended position.

In order to hold the shoe 28 in the extended rigid locked position there is provided a pivoted latch 46. The latch 46 is pivoted on the pivot 24 and has an upper end provided with spaced teeth 48 (only one shown) and an abutment 50. The lower half of the pivoted latch has a handle 52 which projects from the inside of the leg 12 where it may be readily engaged and be pressed inwardly for operation. A spring 54 mounted between the leg and the latch urges its upper end inwardly of the leg. The spring is conveniently held in place by projections 56 and 58 formed respectively from the material of the leg and latch. The abutment 50 may be likewise formed from the latch. The body of the shoe 28 has two notches 60 which receive the teeth 48 to form an engagement between the latch and the shoe. The lower surface of the tongue 34 is sloped as indicated at 49 and the upper edges of the teeth 48 are slightly curved so that the teeth will ride up on the tongue as the shoe moves into its fully locked position and thus automatically cause en-

agement of the latch with the shoe. The abutment 50 keeps the teeth positioned so that their curved edges will be in alignment with and readily engage the slope 49 as the shoe moves toward the latch. To disengage the latch and fold the legs it is only necessary to depress the handle 52, disengaging the teeth 48 from the shoe. Thereafter the shoe is free to slide in the slot 40 permitting the legs to be folded.

10 Although only one embodiment of the invention is shown and described herein, it will be understood that this application is intended to cover such changes or modifications as come within the spirit of the invention or scope of the following 15 claims.

We claim:

1. A folding ironing table having a pair of rear legs, pivotal connections between said table and said legs permitting said legs to be swung forwardly from extended to folded position, a front leg having a forward wall, a pivotal connection between said front leg and said table spaced forwardly of said first pivotal connections and permitting said front leg to be swung forwardly from 20 extended to fold position, links for connecting said rear legs with said front leg, pivotal connections between said legs and links spaced outwardly of said first and second pivotal connections so that said rear legs and front legs swing 25 in unison between extended and folded positions, a locking rod pivotally mounted to said table at said first pivotal connection, a longitudinally extending slot in said forward wall between the pivotal connection between the front leg and said 30 links and said table, and a shoe rigidly secured to said locking rod, said shoe having a T extending through said slot and engageable with the front side of said wall, said shoe having a tongue spaced from said T and engageable with 35 the rear side of said wall, said T and shoe being aligned with said wall so that in the extended position of said legs said T and shoe press inwardly from opposite sides of said wall to make 40 a frictional lock between said locking rod and said front leg.

2. A folding ironing table as claimed in claim 1 in which there is a notch in said shoe and a latch pivotally mounted on said pivotal connection between said links and said front leg, said latch being spring-biased into locking engagement with 45 said notch in the extended position of said legs.
